UNITED STATES PATENT OFFICE.

EDWARD S. HALL, OF PORTLAND, MAINE.

DESIGN FOR A CARD, &c.

SPECIFICATION forming part of Design No. 24,047, dated February 19, 1895.

Application filed December 27, 1894. Serial No. 533,128. Term of patent 3½ years

To all whom it may concern:

Be it known that I, EDWARD S. HALL, a citizen of the United States, residing at Portland, in the county of Cumberland and State of Maine, have invented and produced a new and original Design for Cards and the Like, of which the following is a specification, reference being had to the accompanying drawing.

In the drawing the design is represented as applied to a card and is shown in plan view.

The leading feature of my design consists of two panels arranged parallel to each other in curved lines with an ornamental scroll at one end of the panels, and with an ornamental vertical panel at the opposite end, this panel being in imitation of a frame and including the picture of a child. Arranged above the two panels first mentioned is a

third panel of less length and width, and the card, note or letter head is still further ornamented as shown in the drawing.

The design as hereinbefore described is included within inclosing lines. Suitable inscriptions may appear in the panels.

I do not limit myself to the design containing the picture of a child in the left hand panel as this picture may be omitted without departing from the invention.

What I claim is—

The design for a card and the like herein shown and described.

EDWARD S. HALL.
